UNITED STATES PATENT OFFICE.

HIRAM HANNA, OF COLUMBUS, OHIO.

KITCHEN-CABINET.

SPECIFICATION forming part of Letters Patent No. 295,120, dated March 11, 1884.

Application filed May 28, 1883. (No model.)

To all whom it may concern:

Be it known that I, HIRAM HANNA, of Columbus, in the county of Franklin and State of Ohio, have invented certain new and useful Improvements in Kitchen-Cabinets; and I do hereby declare the following to be a full, clear, and exact description of the invention, such as will enable others skilled in the art to which it appertains to make and use the same.

My invention relates to an improvement in kitchen-cabinets, the object of the same being to provide a device of this character which shall be simple and economical in construction and neat and finished in appearance; and with these objects in view my invention consists in certain details of construction and combinations of parts, as will be hereinafter described, and pointed out in the claim.

In the accompanying drawings, Figure 1 is a view in perspective of my improvement with the doors and drawers all opened. Fig. 2 is a detached view of the under side of the cover of the flour-bin. Fig. 3 is a view in vertical section through the flour-bin. Fig. 4 is a vertical section taken through the sliding shelf.

The frame of this cabinet is composed of the sides A, A, floor B, and top C. A drawer, D, fits beneath the top C, and is supported by and slides on the partition E. One portion of this drawer is divided into sections adapted to hold the different spices, the remaining portion of the drawer being used as a receptacle for the cutlery. From this horizontal partition E to the floor B extends the vertical partition F, which divides the lower portion of the cabinet into two compartments. One compartment, G, is provided on each side with a track, on which is adapted to slide the shelf H, the latter being covered with tin, on which is placed bread or pastry. The rear end of this shelf is provided with a vertical portion, a, adapted, when pulled outward, as shown in Fig. 1, to abut against a stop, r, fastened to the under side of the partition E. It will thus be seen that when the shelf is loaded it may be pulled forward and left in that position without danger of falling, the end upright piece striking on the stop on the under side of the partition E, serving to keep the shelf in a horizontal position.

The compartment K is adapted to receive 55 the meal-bin L. The forward end of this bin is provided with a roller, b, as shown in Fig. 1, adapted to support the forward end of the same. This bin is also provided with side rollers, c, Fig. 3, adapted to travel on 60 the tracks d, secured to the floor and sides of the compartments K. The rollers d, striking against the upright pieces e e, prevent the bin from being pulled out of the compartment. The bin L is preferably pro- 65 vided with the removable partitions h, thereby adapting it to receive and keep separate several different kinds of meal, the same being ventilated by means of the air-passages i i, covered with fine netting. This bin is 70 also provided with the removable cover M, which is held in place by the tenon k on the bin entering the mortise l in the lower side of the cover, and also by a portion of the cover fitting down in the bin. A por- 75 tion of this cover is cut away, and a wire-netting stretched across the under side, forming a sieve, O. This sieve is protected by a cover, N, which is adapted to be used as a kneading-board. On the under side of this 80 cover M, and on each side of the sieve O, are secured the guides o, adapted to receive the pan P, adapted to catch the sifted flour or meal.

On the top C of the cabinet is the com- 85 partment Q, secured in position by tenons on the said compartment, fitting in the mortises formed in the top C. This compartment is subdivided into two parts by the horizontal partition p. This compartment is adapted to 90 receive dishes and table-ware, and, if not necessary, may be dispensed with.

Having fully described my invention, what I claim as new, and desire to secure by Letters Patent, is—

In a kitchen-cabinet, the combination, with the meal-bin L, having a removable cover, the latter being provided with the door N and screen O, situated below the door, of the detachable drawer secured to the under side of 100 the cover below the screen, substantially as set forth.

In testimony whereof I have signed this specification in the presence of two sub- 95 scribing witnesses.

Witnesses: HIRAM HANNA.
J. V. LEE,
JAS. M. WOODBURY.
